The broken lines showing the electronic mobile device is provided for the purpose of illustrating environmental structure; whereas the broken lines showing the display screens and elements of the graphical user interface illustrate portions of the article. All of the aforementioned subject matters shown in broken lines do not form part of the claimed design.

The appearance of the animated user interface sequentially transitions between the images shown in FIGS. 1-12. The process or period in which one image transitions to another forms no part of the claimed design.

1 Claim, 12 Drawing Sheets
